CLAIM

The ornamental design for a display cart for food, particularly soft pretzels, and the like, as shown and described.

DESCRIPTION

FIG. 1 is a side elevation view of a display cart for food, particularly soft pretzels, and the like showing my new design;

FIG. 2 is an end elevation view thereof;

FIG. 3 is a side elevation view thereof opposite from that of FIG. 1; and

FIG. 4 is an end elevation view thereof opposite from that of FIG. 2.

The top of the display cart is substantially flat and unornamented.
